(57) **CLAIM**

The ornamental design for a patella osteotomy guide, as shown and described.

DESCRIPTION

FIG. 1 is a perspective view of a patella osteotomy guide shown in an environment illustrating our new design;

FIG. 2 is a front end elevation view of the patella osteotomy guide shown removed from its environment in order to show aspects of the design that are not apparent in the perspective view;

FIG. 3 is a rear end elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines shown that are immediately adjacent the shaded areas represent unclaimed boundaries while the dot-dash broken lines are directed to environment and are for illustrative purposes only; the broken lines form no part of the claimed design.
